UNITED STATES PATENT OFFICE.

JULIUS G. ZWICKER, OF BERKELEY, CALIFORNIA, ASSIGNOR, BY MESNE ASSIGNMENTS, TO EDWIN L. POWELL, OF NEW ORLEANS, LOUISIANA.

PRESS.

Application filed June 25, 1923. Serial No. 647,465.

To all whom it may concern:

Be it known that I, JULIUS G. ZWICKER, a citizen of the United States, residing at Berkeley, in the county of Alameda and State of California, have invented certain new and useful Improvements in Presses, of which the following is a specification.

My invention relates to fluid pressure operated presses of a type adapted for the compression or molding of plastic substances.

The object of my invention is to provide a press of the type described which is capable of exerting effective pressure simultaneously from all directions in a given plane. A further object is to provide such a press which has a minimum number of parts, and which is, therefore, simple in construction and operation. These and other objects will be brought out in the following complete description of a preferred embodiment of my invention, which is particularly adapted for the pressing or molding of cylindrical or tubular objects of plastic material, such for example as a cement concrete mixture. It will be obvious, however, that my invention is not restricted to the described use, but may be adapted with equal success to any other purpose for which presses of this general type are suitable. Moreover, it is to be understood that changes may be made in the form and construction of the device as herein described and illustrated, without departing from the spirit of the invention as expressed in the claims hereto appended.

My invention will now be fully described with reference to the accompanying drawings, wherein:

Fig. 1 is a sectional plan view of my press, taken on the line 1—1 of Fig. 2.

Fig. 2 is a vertical section taken principally on the line 2—2 of Fig. 1.

Fig. 3 is a vertical section taken on the line 3—3 of Fig. 1, the mold bars being omitted.

Fig. 4 is a sectional plan taken on the line 4—4 of Fig. 3.

Fig. 5 is a fragmental vertical section, enlarged, of one of the mold bars and the supporting means therefor.

Fig. 6 is a fragmental horizontal section, enlarged, of a number of the mold bars, showing their relation to each other and to the operating ring. 55

Fig. 7 is a side elevation, enlarged, of one of the mold bars.

In the drawings, and referring for the moment to Figs. 1 and 2, the reference numerals 1 designate fixed supporting columns, of which there are preferably four, equally spaced as shown. Each column 1 carries a fixed collar or bracket 2, in which is journaled a vertical train of intermeshing spur gears comprising an upper gear 3, a lower gear 4, and a pair of intermediate idlers 5. The upper gears 3 support, by means of rack members 6, a ring 7, and the lower gears 4 similarly support, by means of rack members 8, a ring 9, said ring 9 being positioned below and in vertical alignment with the ring 7. On account of the relations of the gear trains 3, 4, 5 and the racks 6 and 8, any vertical movement of the upper ring 7 will cause a corresponding but opposite movement of the lower ring 9, and, on account of the relatively greater weight of the upper ring 7, the rings normally tend to approach each other, the upper ring 7 moving down and the lower ring 9 moving up. The rings 7 and 9 have no rotative or horizontal movement, and, if desired, any suitable means for preventing such movement may be provided, but such means have been omitted from the drawings as being non-essential to the operation of the device. 75 80 85

The vertical movement of the rings 7 and 9 is limited by guide rods 10, Fig. 3, which are fixed in lugs 11 at the periphery of the upper ring 7, and pass freely through lugs 12 projecting from the lower ring 9. Said rods are provided with spaced nuts 13 and 14 to limit, respectively, the separation and approach of the rings 7 and 9. By adjusting the nuts 14 upon the rods 10, the relative movement of said rings toward each other may be varied, for a purpose which will become apparent later. 90 95

The collars 2 support fixed brackets 15, Fig. 2, extending into the space between the rings 7 and 9, and carrying a fixed

annular member 16, which serves as a support for the mold bars 17. The mold itself is formed of a plurality of bars 17, disposed vertically within the movable rings 7 and 9 and the annular support 16, and closely spaced, as shown in Figs. 1, 2 and 6, to form, in effect, a cylinder composed of adjacent bars separated by narrow spaces or slits.

10 Each mold bar 17 is provided on its outer edge with pins 18, Figs. 2 and 5, which pass freely through holes or guide-ways 19 in the annular support 16. In the drawings, I have shown each bar 17 as provided with 15 three such pins 18, but more or less may be used as necessary. The mold bars 17 are thus supported, in their proper positions, by the pins 18 and the annular support 16, and are permitted to have a limited 20 radial movement, to cause the mold to contract and expand.

It is to be understood that any other suitable means for supporting the mold bars 17 may be substituted for the ring 16 and the 25 pins 18, the construction shown and described above being typical of any supporting means which will permit said bars 17 to have a limited radial movement.

The mold bars 17 are provided, on their 30 outer edges, with oppositely inclined surfaces 20, which lie against and cooperate with the truncated conical inner peripheries 21 of the rings 7 and 9, as shown in Fig. 2. Said bars are also provided with inclined 35 slots 22, Figs. 2 and 7, parallel to the inclined surfaces 20, and adapted to be engaged by conical annular flanges 23 secured to the rings 7 and 9 as shown in said Fig. 2. Therefore, when the rings 7 and 9 are 40 separated, by opposite vertical movements, the bars 17 are moved radially inwardly, to contract the mold, and when said rings are moved together, the bars 17 are drawn outwardly to expand the mold, by the engagement of the conical flanges 23 with the inclined slots 22.

The upper ring 7 has an annular chamber 24, Figs. 2, 3 and 4, extending upwardly from its lower surface, and forming the 50 working cylinder. An annular piston 25 operates in said cylinder, suitable packing rings or glands 26 being provided to prevent leakage. The annular piston 25 rests loosely upon a series of studs 27 secured to and projecting upwardly from the lower ring 9. The working fluid is admitted to and discharged from the annular cylinder 24 through a connection 28, Fig. 2, controlled by any suitable means, as for example a three-way valve 29. Thus when 60 said valve 29 is operated to admit fluid under pressure to the annular cylinder 24, the upper ring 7 is forced upwardly, and at the same time the lower ring 9 is forced 65 downwardly by the action of the annular

piston 25 and the studs 27. This separation of the rings 7 and 9 contracts the mold by moving the bars 17 inwardly, as described above. When the valve 29 is operated to cut off the fluid supply, and permit the discharge of the fluid within the annular cylinder 24, the upper ring 7 descends by its own weight, and lifts the lower ring 9 through the agency of the gear trains 3, 4, 5, and the racks 6 and 8, thereby expanding 75 the mold. The amount of movement of the mold bars 17 is regulated by changing the positions of the adjustable nuts 14 on the guide rods 10, said nuts limiting the approach of the rings 7 and 9 and consequently the outward movement of the mold bars. The lower nuts 13 are preferably secured 80 permanently upon the rods 14, by any convenient means not shown in the drawings, to prevent their accidental removal and consequent damage to the machine.

It will be observed that the gear trains 3, 4, 5 and the racks 6 and 8 have no other function, than to support the weight of the rings 7 and 8 and to equalize the movements 90 thereof, and therefore are not subject to the working force of the power fluid, such force being exerted directly upon the two rings through the annular piston 25 and the studs 27. On account of this direct application 95 of the working force, no heavy supporting or guiding frame is necessary, and the rings 7 and 9 can be sufficiently held and guided by said racks and gear trains.

It is also to be noted that, on account of 100 the individual movement of the mold bars 17, the spaces between said bars are caused to expand and contract with the expansion and contraction of the mold. This permits the mold to be easily cleaned, as any solid particles that may lodge between the bars 17 during the contraction of the mold are loosened when said bars are separated by the subsequent expansion of the mold, and may be easily removed by washing or other suitable means. On account of this construction 105 I am enabled to space the bars 17 very closely, a space of one one-hundredth of an inch being sufficient in actual practice. Moreover, the bars 17 may easily be removed and 110 replaced with similar bars of greater width, to provide a mold of smaller diameter.

As before stated, my device is applicable 115 for compressing either solid or hollow articles. If it is used for the latter, such for example as sections of pipe, a suitable core may be employed, but as such core forms no part of the present invention, it is indicated only by the dotted line 30 in Fig. 1. Moreover, my press obviously need not 120 be restricted to the cylindrical form as shown and above described, the essential principles of the invention, as expressed in the following claims, applying equally well to forms in which the mold is polygonal or 125 130

of other shapes capable of being contracted and expanded in the manner described.

I claim:—

1. A press comprising a plurality of movable bars forming a mold, said bars having inclined outer faces; a pair of members surrounding said bars and adapted for engagement with the inclined faces thereof; and means for moving said members, simultaneously and in opposite directions, to effect the contraction and expansion of said mold. 70
2. A press comprising a plurality of movable bars forming a mold, said bars having oppositely directed inclined faces on their backs; a pair of members surrounding said bars and adapted for respective engagement with the inclined faces thereof; and means for moving said members longitudinally of said mold, in opposite directions simultaneously, to effect the contraction and expansion thereof. 75
3. A press comprising a plurality of laterally movable spaced bars forming a mold, said bars having oppositely directed inclined faces on their backs; a pair of members surrounding said bars and adapted for respective engagement with the inclined faces thereof; and means for moving said members longitudinally of the mold to effect the contraction thereof, comprising a cylinder associated with one of said members, a piston operable in said cylinder and associated with the other member, and means 80 for admitting fluid under pressure to said cylinder. 85
4. A press comprising a plurality of laterally movable spaced bars forming a mold, said bars having oppositely directed inclined faces on their backs; a pair of members surrounding said bars and adapted for respective engagement with the inclined faces thereof; means for moving said members in opposite directions simultaneously to effect the contraction and expansion of the mold; and means associated with said members for equalizing the movements thereof. 90
5. A press comprising a plurality of laterally movable spaced bars forming a mold, said bars having oppositely directed inclined faces on their backs; a pair of members surrounding said bars and adapted for respective engagement with the inclined faces thereof; means for moving said members in opposite directions simultaneously to effect the contraction and expansion of the mold; and supporting means associated with said members for equalizing their movements. 100
6. A press comprising a plurality of laterally movable spaced bars forming a mold; a pair of members surrounding said bars and movable longitudinally of the mold; means for translating the longitudinal movement of said members into lateral contractive and expansive movement of said mold; and means for moving said members simultaneously in opposite directions. 105
7. A press comprising a plurality of laterally movable spaced bars forming a mold; a pair of members surrounding said bars and movable longitudinally of the mold; means for translating the longitudinal movement of said members into lateral movement of said bars to contract and expand the mold; means for moving said members simultaneously in opposite directions; and devices for equalizing the movements of said members. 110
8. A press comprising a plurality of laterally movable spaced bars forming a mold; a pair of members surrounding said bars and movable longitudinally of the mold; means for translating the longitudinal movement of said members into lateral movement of said bars to contract and expand the mold; means for moving said members simultaneously in opposite directions; and devices for movably supporting said members and for equalizing the movements thereof. 115
9. A press comprising a plurality of laterally movable spaced bars forming a mold; means for supporting said bars; means for moving said bars outwardly to expand the mold; a member surrounding said bars and movable longitudinally of the mold; and means for translating the longitudinal movement of said member into lateral movement of said bars to contract the mold. 120
10. A press comprising a mold capable of contraction and expansion; a pair of members surrounding said mold and movable longitudinally thereof; means for translating the longitudinal movement of said members into lateral contractive and expansive movement of said mold; and means for moving said members simultaneously in opposite directions. 125
11. A press comprising a mold capable of contraction and expansion; a pair of members surrounding said mold and movable longitudinally thereof; means for translating the longitudinal movement of said members into lateral contractive and expansive movement of said mold; and means for moving said members simultaneously in opposite directions, comprising a cylinder associated with one of said members, a piston operable in said cylinder and connected with the other member, and means for admitting fluid under pressure to said cylinder. 130
12. A press comprising a mold capable of contraction and expansion; a pair of members surrounding said mold and movable longitudinally thereof; means for translating the longitudinal movement of said members into lateral contractive and expansive move-

ment of said mold; and means for moving said members simultaneously in opposite directions, comprising an annular cylinder associated with one of said members and surrounding said mold, an annular piston operable in said cylinder and connected with the other member; and means for admitting fluid under pressure to said cylinder.

13. A press comprising a mold capable of contraction and expansion; a pair of members surrounding said mold and movable longitudinally thereof, one of said members having a substantially annular channel forming a cylinder; a substantially annular piston operable in said cylinder; a connection between said piston and the other member; means for admitting fluid under pressure to said cylinder to cause the relative movement of said members; and means for translating the longitudinal movement of said members into contractive movement of said mold.

14. In a press having a mold adapted for contraction, a member surrounding said mold and having a substantially annular channel forming a cylinder; a substantially annular piston operable in said cylinder; means for admitting fluid under pressure to said cylinder; and means for translating the relative movement of said member and said piston into contractive movement of said mold.

15. A press comprising a mold adapted

for lateral contraction and expansion; a pair of members surrounding said mold and adapted for substantially vertical movement toward and away from each other; means for translating the substantially vertical movement of said members into contractive and expansive movement of said mold; controllable power devices for separating said members to cause the contraction of the mold; and means actuated by the weight of one of said members for causing them to move toward each other to cause the expansion of the mold.

16. A press comprising a plurality of movable bars forming a mold, said bars being formed with inclined slots; a member surrounding said bars and adapted for engagement with said slots; and means for moving said member longitudinally of the mold to effect the contraction and expansion thereof.

17. A press comprising a plurality of movable bars forming a mold, said bars being formed with inclined slots; a pair of members surrounding said bars and adapted for engagement with said slots; and means for moving said members simultaneously and in opposite directions, to effect the contraction and expansion of said mold.

In testimony whereof I have signed my name to this specification.

JULIUS G. ZWICKER.
